Primary Examiner — Paula Greene(74) *Attorney, Agent, or Firm* — Sonya C. Harris; Invention Services Gaff Myer IPS(57) **CLAIM**

The ornamental design for the LED magnifier, as shown and described.

DESCRIPTION

FIG. 1 is a left front perspective view of my design;
FIG. 2 is a front elevational view of my design;
FIG. 3 is a rear elevational view of my design;
FIG. 4 is a right side elevational view of my design;
FIG. 5 is an opposite side elevational view of my design;
FIG. 6 is an end view of my design; and,
FIG. 7 is an opposite end view of my design.
